CLAIM

The ornamental design for a sliding door rail, as shown and described.

DESCRIPTION

FIG. 1 is a perspective view of a sliding door rail.

FIG. 2 is an alternative perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof.

FIG. 8 is a bottom plan view thereof; and,

FIG. 9 illustrates an example environment in which the sliding door rail may be used (e.g., in conjunction with a spacer).

The broken lines shown in FIG. 9 depict an environment of use and form no part of the claimed design.
